UNITED STATES PATENT OFFICE.

RUDOLPH BECKER, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

RUFFLING MECHANISM FOR SEWING MACHINES.

Application filed September 29, 1921. Serial No. 504,095.

To all whom it may concern:

Be it known that I, RUDOLPH BECKER, a citizen of the United States, residing at Roselle Park, in the county of Union and 5 State of New Jersey, have invented certain new and useful Improvements in Ruffling Mechanisms for Sewing Machines, of which the following is a specification, reference being had therein to the accompanying drawings.

This invention relates to sewing machines and has for an object to provide an improved form of ruffling or plaiting mechanism of sturdy construction and adapted, 15 more particularly, for use in the operation of sewing hat linings or "tips" and so constructed that the operative parts may be lifted clear of the work-support to facilitate insertion and removal of the work. 20 A further object of the invention is to provide an improved and simplified form of actuating mechanism for operating the ruffling blade, whereby the device may be caused to form but one fold or plait during 25 the formation of a plurality of stitches.

A sewing machine equipped with the present plaiting mechanism is adapted for use in conjunction with the work-holding and trimming devices disclosed in my copending 30 application Serial No. 504,094, filed herewith. The plaiting blade is preferably mounted for up and down yielding movement at the lower end of a carrier-arm which is fixed to a horizontal rock-shaft 35 journaled in fixed bearings on the sewing machine goose-neck. This rock-shaft receives its motion from a cam mounted adjacent the base of the goose-neck and connected by suitable gears to the sewing machine main-shaft which extends horizontally 40 below the cloth-plate.

Through the described gearing the cam is given one rotation for a plurality of rotations of the main-shaft and the ruffling 45 blade is thus given one complete reciprocation at intervals of a plurality of stitches. The length of the stroke of the ruffling blade may be varied by a suitable adjustment in the train of actuating connections between 50 the cam and the rock-shaft which carries the ruffling blade. A novel and important feature of the present improvement lies in the provision of a separating blade or plate

which is resiliently mounted on the sewing machine presser-foot yet acts to lift the 55 ruffling blade from the sewing machine cloth-plate when the presser-foot is lifted for insertion or removal of work.

In the accompanying drawings, Fig. 1 is a side elevation of a sewing machine embodying the invention. Fig. 2 is a fragmentary front elevation of the same. Fig. 3 is a section on the line 3—3, Fig. 1. Fig. 4 is a view similar to Fig. 2 but on a larger scale to show the action of the ruffler-blade. 65 Fig. 5 is a plan view of the parts adjacent the sewing point. Fig. 6 is a fragmentary rear-end elevation of the machine showing the ruffler-actuating mechanism. Fig. 7 is a fragmentary rear-side elevation of the 70 machine showing the ruffler-actuating mechanism and Fig. 8 is a disassembled perspective view of the ruffler-blade and the means whereby it is mounted on its carrier-arm.

In the embodiment of the invention illustrated the sewing machine comprises a base 1, cloth-plate 2, and goose-neck 3 terminating in the head 4 in which are journaled the usual needle- and presser-bars 5 and 6, respectively, carrying the needle 7 and presser-foot 8. The presser-foot is spring-pressed as usual toward the work and may be lifted by swinging the usual cam-lever 9. The needle-bar is reciprocated by the usual pitman connection 10 with a crank-arm 11 on the needle-operating shaft 12 which is rocked by the usual pitman connection 13 with a crank-pin 14 on the balance-wheel 15 mounted on the main-shaft 16; the latter extending below the cloth-plate 2 and carrying the usual rotary chain-stitch looper 17. The usual four-motion feed-dog 18 cooperates with the presser-foot 8 to feed the work.

The plaiting or ruffling blade 19 is journaled on the horizontal pin 20 mounted on the lower end of the carrier-arm 21 which is fixed at its upper end to the ruffler-operating rock-shaft 22 journaled in the fixed bearings 23 and 24 on the goose-neck 3. A 95 coil spring 25, Fig. 5, surrounding the pin 20 yieldingly holds the toothed end 26 of the ruffler-blade depressed toward the separating blade 27 which is preferably formed at the end of the forward leg of the thin, 100 resilient, U-shaped arm 28, Fig. 5, which

is strengthened by the rib 29 and the rearward leg of which is rigidly secured to the presser-foot 8, as by brazing or other suitable means.

5 The ruffler-carrying rock-shaft 22 has fixed to its rearward end a depending slotted arm 30 adjustably carrying a lateral pin 31 entering a block 32 which is received by the slot 33 in the upwardly extending arm 34 10 of a lever pivoted at 35 to the goose-neck. The downwardly extending arm 36 of this lever is pivotally connected at 37 to one end of the pitman 38, the opposite end of which is forked at 39 to embrace the hub 40 of 15 the gear 41 formed in one face with the cam-groove 42 which receives the follower roll 43 mounted on the pitman 38. The cam-groove 42 is concentric with the center of the gear 41 throughout the major portion 20 of its circumference but has an eccentric portion 45 for imparting one complete reciprocation to the pitman 38 per revolution of the gear 41. By means of the reduction gears 46, 47 and 48, the cam-gear 25 41 is driven by the main-shaft 16 at a speed of one revolution to say, five revolutions of the shaft 16. The blade 19 is thus caused to produce one plait or fold *a* in the material *b* for each five stitches made by the machine.

The arm 28 yields sufficiently to permit the slight vertical movement of the presser-foot caused by the rising and falling movements of the feed-dog 18 without lifting the 35 separator-blade 27 from the main body *c* of the work. The yielding action of the arm 28 also retains the separator-blade 27 at a constant level while the presser-foot 8 is lifted periodically to a higher level by 40 the feed-dog, as the ruffling blade moves a fold of material under the toe end of the presser-foot. The presser-foot, being higher than the separator-blade at this time, permits the fold to be carried horizontally to 45 and deposited under the presser-foot, which thereupon clamps the fold upon the cloth-plate without distortion or loss of control of the fold. As shown in Figs. 4 and 5, the separator-blade 27 underlaps the toe end of 50 the presser-foot, so that control of the fold in the work will be retained by the coaction of the blade 19 and plate 27 until such fold is deposited under the presser-foot.

When the presser-foot is lifted clear of the work, however, the resilient arm 29 is 55 stiff enough to lift the plate 27 and blade 19 against the relatively light tension of the spring 25 to the position shown in Fig. 2, thus permitting ready removal and insertion 60 of the work. Mounted on the cloth-plate 2 is a suitable rest 49 and guide 50 for the edge of the lining strip *b* or other material to be plaited. The rest 49 is spaced above the cloth plate sufficiently to permit the 65 passage of the main body *c* of the work

thereunder and the guide 50 is adjustably mounted on the rest 49 by a screw and slot fastening 50'.

In lieu of or in addition to the edge-guide 50 for the material to be plaited or 70 ruffled, the edge-guide 51 may be employed. This latter guide is formed with a shank 52 which is secured by a thumb-screw 53 to the arm 28 carrying the separator-blade 27. The thumb-screw 53 passes through a 75 slot 54 in the shank 52, thus permitting adjustment of the guide 51 transversely of the line of seam formation.

In the operation of sewing hat linings the main body of the work is in the form 80 of a square blank of stiffened material which is carried by a turn-table, such, for example, as disclosed in my said copending application, for presenting the work in an oval path to the needle. During the sewing 85 operation portions of this blank, particularly the corners thereof, project a considerable distance to the right of the line of seam-formation and it is for this reason that the rest or support 49 for the guide 50 is spaced 90 above the cloth-plate 2 for a considerable distance to the right of the line of seam-formation.

Having thus set forth the nature of the invention, what I claim herein is—

1. The combination with a sewing machine presser-foot and feed-dog, of a reciprocating ruffling blade mounted independently of said presser-foot, and a separator-blade carried by the presser-foot and underlapping said ruffling blade and the toe end of the presser-foot.

2. The combination with a sewing machine presser-foot and feed-dog, of a reciprocating ruffling blade mounted independently of the presser-foot and having a vertically yielding operative extremity, a separator-blade underlying said ruffling blade, and a yielding arm fixed at one end relative to said presser-foot and carrying said separator-blade, said arm being stiff enough to lift the operative extremity of the ruffling blade when the presser-foot is lifted.

3. A sewing machine having in combination, a frame including a bed and overhanging goose-neck, stitch-forming and feeding mechanisms incorporated in said frame and including a reciprocating needle, feed-dog and presser-foot, means for lifting the presser-foot, a rock-shaft journaled in fixed bearings on said goose-neck, means for rocking said shaft, an arm on said shaft, a ruffling blade pivotally carried by said arm, and a separator-blade connected to the presser-foot and underlying said ruffling blade.

4. The combination with a sewing machine needle, presser-foot and feed-dog, of a reciprocating ruffling blade mounted independently of said presser-foot, a sepa-

rator-blade underlying said ruffling blade, a yielding U-shaped arm disposed at one side of the needle and carrying said separator-blade and fixedly connected to said presser-foot, and an edge-guide mounted on said yielding arm at the same side of the needle as said arm.

5. A ruffling mechanism for sewing machines comprising, a rock-shaft, a ruffling blade actuated by said rock-shaft, and means for rocking said shaft including a cam having active and dwell portions, gearing for driving said cam from the main-shaft of the sewing machine at a reduced speed, an arm on said rock-shaft, and an operative connection between said cam and arm.

6. A ruffling mechanism for sewing machines comprising, a rock-shaft, a ruffling blade actuated by said rock-shaft, and means 20 for rocking said shaft including a cam having active and dwell portions, gearing for driving said cam from the main-shaft of the sewing machine at a reduced speed, an arm on said rock-shaft, a lever adjustably 25 connected to said arm, a pitman secured at one end to said lever, means for supporting the other end of said pitman for endwise movement, and a follower carried by said pitman and in operative engagement with 30 said cam.

In testimony whereof, I have signed my name to this specification.

RUDOLPH BECKER.
